UNITED STATES PATENT OFFICE

169,268

PLATE OR THE LIKE

Otto J. Lund, Valley Stream, N. Y., assignor to Castleton China Incorporated, New York, N. Y., a corporation of New York

Application July 13, 1951, Serial No. 15,860

Term of patent 14 years

(Cl. D44—15)

To all whom it may concern:

Be it known that I, Otto J. Lund, a citizen of Denmark, residing at Valley Stream, Long Island, county of Nassau, State of New York, have invented a new, original, and ornamental Design for a Plate or the Like, of which the following is a specification, reference being had to the accompanying drawing, forming part thereof.

In the drawing:

Fig. 1 is a top plan view of a plate, showing my new design, and

Fig. 2 is a side elevational view thereof.

I claim:

The ornamental design for a plate or the like, as shown.

OTTO J. LUND.
